United States Patent

Des. 238,259
Patented Dec. 30, 1975

238,259

REFUSE TRAILER

Phillip J. Sweet, Buck C. Hamlet, and David L. Sweet,
Fresno, Calif., assignors to American Carrier Equipment

Filed July 29, 1974, Ser. No. 492,614

Term of patent 14 years

Int. Cl. D12—10

U.S. Cl. D12—15

FIG. 1.

FIG. 2.

FIG. 3.

FIG. 1 is a top plan view of a refuse trailer showing our new design, it being understood that the fragmentary criss-cross patterns are continuous throughout the area shown.

FIG. 2 is a side elevational view thereof.

FIG. 3 is a bottom plan view thereof.

FIG. 4 is a front elevational view thereof.

FIG. 5 is a rear elevational view thereof.

We claim:

The ornamental design for a refuse trailer, as shown.
